UNITED STATES PATENT OFFICE.

SAMUEL VANSTONE, OF PROVIDENCE, RHODE ISLAND, ASSIGNOR TO THE PATENT DEVELOPMENT COMPANY, OF PROVIDENCE, RHODE ISLAND, A CORPORATION OF RHODE ISLAND.

FORGING-MACHINE.

SPECIFICATION forming part of Letters Patent No. 694,808, dated March 4, 1902.

Application filed April 11, 1901. Serial No. 55,378. (No model.)

To all whom it may concern:

Be it known that I, SAMUEL VANSTONE, a citizen of the United States, and a resident of Providence, in the county of Providence and State of Rhode Island, have made a certain new and useful Invention in Forging-Machines; and I declare the following to be a full, clear, and exact description of the same, such as will enable others skilled in the art to which it appertains to make and use the invention, reference being had to the accompanying drawings, and to letters of reference marked thereon, which form a part of this specification.

15 This invention has relation to forging-machines, and has for its object the provision of a machine of this character which will draw or forge tapers upon the tangs of files or other tools, upon staples, spindles, coach-screws, 20 marlin-spikes, and a variety of other articles too numerous to mention, the taper being quickly formed in one operation and in an exactly even manner upon all sides of the article.

With this object in view the invention consists in the novel construction and combination of parts, all as hereinafter described, and pointed out in the appended claims.

Referring to the accompanying drawings, Figure 1 is a top plan view of a double machine for forming tapers upon the tangs of files. Fig. 2 is a top plan view of a single acting machine for the same purpose. Fig. 3 is a section on the line 3 3, Fig. 2. Fig. 4 is a detail view showing a single die secured 35 in the end of one of the levers. Fig. 5 is a detail view showing the double die pressed into the heated blank. Fig. 6 is a detail view showing the position of the dies as the separated blank leaves them. Fig. 7 is a detail view of a round rod or blank for a spindle. Fig. 8 shows the same separated in the center by means of a pull or draw and without dies. Fig. 9 shows a flat blank separated in like manner to the rod above described. Fig. 40 45 10 is an edge view of the blank of Fig. 9. Fig. 11 illustrates in detail the central portion of a file-blank, in which the shoulders at the base of the tang are formed therein previously to the operation of the machine thereupon, 50 in which case the dies are dispensed with.

I will first proceed to describe the double machine.

In the drawings the letter A designates the framework, and B B rotary shafts at opposite ends thereof, having a bevel-gear driving 55 connection with the power-shaft b. Upon the table of the machine, at opposite end portions thereof, reciprocate in suitable guideways a, the slides C C, operated by crank-and-pitman connection c with shafts B and carrying the 60 pattern-cams C' C', which cams commence with a short decided obliquity at c' for the purpose of forming the shoulders at the base of the tang and continue in a less decided or lower obliquity for the tapered sides of 65 the tang.

D D are horizontally-acting levers pivoted at d and having rollers d' at the outer extremities of their long arms in engagement with the pattern-cams aforesaid and having 70 the inner extremities of their short arms arranged to work in slots or recesses e of the die-heads E E, which die-heads are adapted for reciprocation transversely of the machine in suitable guideways e'.

D' D' are springs acting against the levers D to press the rollers thereof into engagement with the pattern-cams.

e² represents the dies or pressure-plates, forming a part of said heads and presenting 80 oppositely.

F F designate the tongs for grasping the ends of the stock and carried one pair by each of the slides C, such tongs being of toggle-lever character and having the jaws f f bevelled at their forward or inner ends. The toggle-levers of the tongs have a common pivot f' to the slide.

In operation the blank to be worked is placed upon the rests G G, the dies presenting 90 centrally of the lateral faces of the blank and the end portions of the blank being within reach of the tongs. As the slides C C are moved inwardly toward each other by rotation of the shafts B the tongs F are also moved inwardly, the tapered or rounded grasping-faces of the jaws of the tongs allowing them to slip over the end portions of the blank into position for gripping the same, the joint-pin f² of the forward pair of toggles of each pair 95 100

of tongs at the same time dropping into a seat f^3 in an upwardly-projecting spring-arm f^4 .

As the shafts B continue to rotate the slides are now withdrawn or moved outwardly, the retardation of the springs f^4 acting against the joint-pins f^2 , causing the jaws of the tongs to close upon the stock until it is effectively gripped, further withdrawal of such slides and tongs thus causing the jaws to automatically grip the stock tighter and tighter and at the same time to exert a pulling or drawing action thereupon to separate the stock in the center thereof which is heated previously. When the slides and tongs are beginning in their withdrawal, the dies are pressed inwardly into the heated blank to form the shoulders at the base of the file-tangs, the rounded-edge ribs e^3 of said dies gradually closing upon the metal as it is withdrawn therethrough until such edge ribs come together. Center ribs e^4 of the dies aid in parting the metal at the exact center of the blank.

The single-acting machine operates in the same manner as the double machine above described, a single slide C, pattern-cam, pair of tongs, &c., being employed, the metal of the blank being in this case not pulled apart in the center of the blank, but an attenuation of the end portion of the blank being effected. The transversely-reciprocating die-heads may be omitted and the dies inserted directly in the inner end portions of the short arms of the levers D, as shown in Fig. 4, or the dies may be omitted entirely and a blank employed having the shoulders at the base of the tangs already formed therein or the central portion of the stock cut away, as illustrated in Fig. 11.

In forming a taper or point upon round or flat bars or spindles requiring no shoulders, as in Figs. 7 to 10, inclusive, no dies are required. The length of the taper may be regulated by the degree of heat to which the blank is subjected.

Having thus described my invention, what I claim as new, and desire to secure by Letters Patent, is—

1. In a forging-machine, the oppositely-reciprocating gripping means for both end portions of the blank, and devices in connection therewith for causing the grip of both such means to be effected automatically, substantially as specified.

2. In a forging-machine, the reciprocating gripping means for an end portion of the blank, and devices in connection therewith for causing the grip of such means to be ef-

fectected automatically, and gripping means for the opposite end portion of the blank, substantially as specified.

60

3. In a forging-machine, the combination with the reciprocatory gripping means for one end portion of the blank, and gripping means for the opposite end portion of the blank, of a pressure or die device for the heated portion of the blank, and means in connection with such device to cause it to be applied automatically, substantially as specified.

65

4. In a forging-machine, the reciprocatory slides, the jaws carried by said slides, and arranged to grip both end portions of the blank, and means in connection with such jaws to cause them to effect their grip automatically, substantially as specified.

70

5. In a forging-machine, the reciprocatory, gripping means for the end portions of the blank, and the reciprocatory, oppositely-acting dies or pressure-plates, substantially as specified.

75

6. In a forging-machine, the reciprocatory slides, the toggle-lever, automatically-acting tongs pivoted to said slides and arranged to grip the end portions of the blank, and means engaging the joint-pin of said tongs for extending said toggle-levers to automatically effect the initial grip, substantially as specified.

80

7. In a forging-machine, the reciprocatory cam-slides, automatically-acting jaws carried by said slides and arranged to grip the end portions of the blank, the pivoted levers operated by said slides, and the reciprocatory dies or pressure-plates operated by said levers, substantially as specified.

85

8. In a forging-machine, a reciprocatory cam-slide, jaws carried by said slide and arranged to grip the blank, reciprocatory oppositely-acting die-heads, carrying the dies, and the pivoted levers actuated by said slides to reciprocate said die-heads, substantially as specified.

90

9. In a forging-machine, the gripping means for the blank, having the tongs, and means engaging the joint-pin of said tongs, for temporarily retarding the movement thereof, to effect the initial grip, substantially as specified.

95

In testimony whereof I affix my signature in presence of two witnesses.

SAMUEL VANSTONE.
